UNITED STATES PATENT OFFICE.

JAMES P. HOOPER, OF GERMANTOWN, PENNSYLVANIA.

AUTOMATIC BOBBIN-WINDING MECHANISM.

1,121,103.

Specification of Letters Patent. Patented Dec. 15, 1914.

Application filed December 4, 1912. Serial No. 734,843.

To all whom it may concern:

Be it known that I, JAMES P. HOOPER, a citizen of the United States, residing at Germantown, in the county of Philadelphia, State of Pennsylvania, have invented a new and useful Automatic Bobbin-Winding Mechanism, of which the following is a specification.

My invention relates to improvements in automatic bobbin winding.

The object is to provide improved means for automatically feeding the bobbin to the winding mechanism for winding the thread thereon, for catching the thread to be wound on the next bobbin and severing the thread from the wound bobbin and delivering the wound bobbin.

Referring to the drawings, which illustrate by way of example a preferred means for effecting my invention—Figure 1 is a plan view of a double headed machine. Fig. 2 is a section on line 2—2 of Fig. 1. Fig. 3 is a front elevation. Fig. 4 is a plan of the right hand carriage and cam for actuating the guide rod. Fig. 5 is a front elevation of the carriage. Fig. 6 is a section on line 6—6 of Fig. 5. Fig. 7 is an enlarged detail of a portion of Fig. 6. Fig. 8 is a plan of the thread guiding mechanism. Fig. 9 is a front elevation of same. Fig. 10 is a section on line 10—10 of Fig. 9. Fig. 11 is a front elevation of the thread guiding mechanism in the inoperative position. Fig. 12 is a section on line 12—12 of Fig. 11. Fig. 13 is a detail plan of the lever for throwing the thread guide mechanism out of the operative position. Fig. 14 is a plan of the tail stock. Fig. 15 is a front elevation of same. Fig. 16 is a detail plan of the thread cutting mechanism. Fig. 17 is an enlarged detail of same in different positions. Fig. 18 is a front elevation of same. Fig. 19 is a diagrammatic view showing position of the thread at the time of cutting same. Fig. 20 is a section of the driving head. Fig. 21 is a detail of the stop for the driving head. Fig. 22 is a side view of the magazine for the bobbins. Fig. 23 is a similar view showing the same in the delivery position. Fig. 24 is a plan of same. Fig. 25 is a front elevation of same.

Similar numerals refer to similar parts throughout the several views.

For purposes of illustration I have shown the machine in Figs. 1 and 3, with two bobbin heads adapted for operating two bobbins

simultaneously. The bobbins are delivered from magazines to suitable driving head and tail stocks, which are operated to release the bobbins when the same have been wound with the required amount of thread. The driving heads 47, see Figs. 8, 15 and 20, are mounted on the driving spindle 43. Spindle 43 is provided with gear 42 meshing with one set of teeth on idler 41. Idler 41 has another set of teeth meshing with idler gear 40. 40 meshes with 39 on shaft 38. Shaft 38 is provided with gear 37 which meshes with gear 35 on the main driving shaft 30.

The specific construction of a head 47 is illustrated in Fig. 20. On each end of spindle 43 is mounted a driving collar 44. Collar 44 has a pin 45 which engages the projection 46 in the flange of head 47. Head 47 is provided with lugs 48 for coöperating with recesses in the end of the bobbin 49 for driving the bobbin. When the bobbin 49 becomes filled with the thread, the periphery of the thread engages the head 50 on the rod 51, controlled by spring 52, and actuates the pusher 53, which is adjustably secured to the rod 51, see Figs. 7 and 22. The pusher 53 when actuated engages the hanging lever 54 pivotally mounted at 55 on the carriage 56 which is slidably mounted on the guide rods 57 and 58. The lower end of lever 54 has a horizontal projection 59 which slides through a support 60 connected with the carriage 56 and is adapted when pushed forward in the direction of the arrow, see Fig. 7, to engage in a recess or opening 61 in the actuated rod 32. The actuation of the lever 54 by the push member 53 is against the counterweight 62 which normally keeps the extension 59 out of engagement with the recess or opening 61 of rod 32. When the projection 59 is engaged in the recess 61 of rod 32 it is carried backward and forward due to the reciprocating motion of bar 32 actuated by the cam 31. When extension 59 of lever 54 is pushed into engagement with the recess of rod 32 and is then moved by said rod, lever 54 engages with rod 124 and is prevented from disengaging from lever 32, until it has made a complete reciprocation. The springs 120 serve normally to maintain the carriages in initial position and to take up any play.

Secured to the carriage 56 is the rod 63 and to the end of rod 63 is pivotally connected the lever 64 which is connected to the fixed pivot 65 and is provided at its

- lower end with a slot 66 in which operates the pin 67, which pin 67 is adjustably secured in the slot 68 to the bar 69, see Figs. 5 and 14. The bar 69 slides between a raised guide 70 and the roller 71. Rigidly secured to bar 69 is the block 72, and to block 72 is adjustably secured the rod 73 which is slidably mounted on the stationary framework and carries the tail-stock 74.
- 10 This tail-stock 74 carries the spring actuated center 75, see Figs. 14 and 15. The reciprocation of the carriage causes the reciprocation of the tail-stock and consequently the releasing of the bobbin.
- 15 Secured to carriage 56 is the arm 76 which supports the latch lever 77 pivoted at 78, see Figs. 8 and 13. While the bobbin is being released it is desirable to remove the thread from the guide 36 which is accomplished through the moving of the carriage and the arm 76.
- 20 The frame 79 is pivotally mounted on the rod 80 secured to the stationary framework and also on the reciprocating thread guide 25 rod 81, see Fig. 11. On this frame 79 is secured the plate 82. On the underside of plate 82 project the pins 83, there being two in number. Adjacent the plate 82 is the plate 84 provided with part horizontal and 30 part inclined slots 85 into which the pins 83 project. Plate 84 is provided with the pins 86 which project into the vertical slots 87 of the plate 88. Secured to plate 88 is the boss 89, see Fig. 12, to which is secured 35 the rod 90. Rod 90 projects into the slot 91 of lever latch 77. The rod 90 also projects into an aperture in the bracket 92 which forms the supporting connection between arm 76 and the lever latch 77, see Fig. 40 8. It follows therefore that when the carriage moves in the direction of the arrow, Fig. 8, the bracket 92 which is in engagement with the pin 90 will carry the pin and consequently move plate 88 in the T-slot 45 in member 79. The movement of plate 88 to the left also carries the plate 84 to the left due to the engagement of the pins 86 in slots 87. The movement of plate 84 causes it to rise due to the engagement of the pins 83 50 in the slots 85. Upon the elevation of the plate 84 its upper margin engages the thread and lifts the same out of the guide 36 which is continually reciprocating. The projection 93 on plate 84 serves to carry the thread over into a plane of the face of the driving head and the cutting knives hereinafter to be described. When the several plates resume the original position due to the complete reciprocation of the carriage 56 the 55 guide 36 will catch the thread in the slot 94 and will resume winding a new bobbin.
- 60 Arm 96 is secured to the stationary framework 95 and pivotally supports at its upper end the bobbin magazine 97. The plate

99 is pivotally secured at 98 to magazine 97. Secured to the member 96 is the rod 100 which engages a projection 101 on the side of plate 99 to limit its inward movement. Secured also to the stationary framework 70 is the supporting arm 102 which supports the row of empty bobbins when the magazine is in the normal position, but when the magazine is thrown into the outer or delivery position arm 102 permits the bobbin formerly resting thereon to drop to the position shown in Fig. 23, to rest upon the bent extension 103 connected with plate 99. Secured also to bar 95 is the frame 104 upon which is fulcrumed at 105 the bell-crank 80 lever 106. One arm of bell lever 106 is connected by the connecting rod 107 with the magazine 97 near its lower end. Secured to the carriage 56 are the pins 108 and 109. These pins are adapted to actuate the other 85 arm 111 of bell-crank 106 at the proper moment, that is toward the end of its movement in one direction to push the magazine out to deliver a bobbin. Below the magazine and supported thereby is the cradle 110 90 which catches the bobbin as the same moves off the wire support 103 as the magazine is withdrawn away from the same. It is to be noted that this cradle moves through an arc intersecting the driving center of the head. 95 The extension 111 of lever 106 is maintained in its different positions of actuation by a spring detent 112. Upon the first outward movement of the magazine the bobbin which has fallen into the cradle at a previous operation is carried to the position corresponding to the center of the head, whereupon the tail-stock is caused to engage the bobbin and press it sufficiently against the head to maintain it there until the pressure becomes 100 great enough to overcome the spring 113 in the head 47. Meanwhile the thread has been carried over by the projection 93 to the position where the same will lie on the pins 48 projecting from the end of the head, as 110 shown in Fig. 21. The guide 114 secured to the main frame serves to engage the shoulder of the head 47 to limit its spring actuated movement and also serves to stop the head 47 so that the projections 48 will lie in a 115 slightly inclined position as indicated in Fig. 21. The thread which has been carried over by the projection 93 will lie upon the projections 48 of the head 47 and will be held there between the head of the new 120 bobbin and the driving head, due to the pressure of the spring of the tail-stock. When the head 47 is pushed into the operative position as shown in Fig. 15, the shoulder 46 is pushed clear of the guide 114 and into locking engagement with pin 45, so that the head 47 is locked to rotate with shaft 43.

For cutting the thread I have provided the following mechanism: The plates 115 are secured to the stationary framework, as shown 136

in Fig. 15, and form a guide and support for the knife 116 and a guide for knife element 117. The knife element 117 is suitably supported on one of the plates 115 by a slot 5 and pin engagement, see Fig. 16, and is actuated by the engagement with pin 118 and a projection of the tail-stock 74, as indicated in Fig. 15, so that the knife element 117 is forced to straddle the knife 116 and cut the thread 119 therebetween. This cutting operation happens almost simultaneously with the start of the winding of the new bobbin.

The pin 121 projects from the main frame 15 of the device, see Figs. 8, 9, 10, 11, 12 and 13. When the carriage 56 carries bracket 92 in the direction of the arrow, Fig. 8, it causes the lever latch 77 to engage with pin 121 and is thereby operated to move the thread guiding mechanism away from the surface of the winding bobbin and out of the path of travel of the bobbin magazine, which is held in said position during the reciprocation of the carriage.

25 What I claim is:—

1. An automatic bobbin winding machine, comprising bobbin engaging and rotating means, a reciprocating thread guide, a reciprocating actuating member, a movable carriage, means, controlled by the periphery of the full wound bobbin, for locking the carriage with the reciprocating actuating member, and means actuated by the carriage for releasing the filled bobbin from 30 its supporting and rotating means.

2. An automatic bobbin winding machine, comprising bobbin engaging and rotating means, a reciprocating thread guide, a reciprocating actuating member, a movable carriage, means, controlled by the periphery of the full wound bobbin, for locking the carriage with the reciprocating actuating member, and means actuated by the carriage for cutting the thread.

45 3. An automatic bobbin winding machine, comprising bobbin engaging and rotating means, a reciprocating thread guide, a reciprocating actuating member, a movable carriage, means, controlled by the periphery 50 of the full wound bobbin, for locking the carriage with the reciprocating actuating member, a bobbin magazine and means controlled by the carriage for operating the magazine to deliver fresh bobbins.

55 4. In a bobbin winding machine, means for holding, rotating and releasing a bobbin, a reciprocating thread guide, a reciprocating actuating member, a movable carriage, a device for locking the carriage with the reciprocating actuating member, means for actuating the locking device controlled by the periphery of the full wound bobbin.

65 5. In a bobbin winding machine, a reciprocating actuating member, a movable car-

riage, a device for locking the carriage with the actuating member, means, controlled by the periphery of the full wound bobbin, for actuating the locking device, and means for maintaining the locking device in the locking position after a preliminary movement 70 of the carriage and until a full forward and back reciprocation thereof.

6. In a bobbin winding machine, a reciprocating actuating member, a movable carriage, a device for locking the carriage with the actuating member, means, controlled by the periphery of the full wound bobbin, for actuating the locking device, and head and tail stocks for engaging, rotating and releasing the bobbin, said engaging and rotating and releasing movements being controlled by the reciprocating carriage.

7. In a bobbin winding machine, comprising a bobbin holding device adapted to support, rotate and release the same, a reciprocating actuating member, a movable carriage, a device for locking the carriage with the reciprocating actuating member, means, controlled by the periphery of the full wound bobbin, for actuating the locking device, a thread guide and means controlled by the carriage for engaging and disengaging the thread with the thread 90 guide.

8. In a bobbin winding machine, a reciprocating actuating member, a movable carriage, a device for locking the carriage with the actuating member, means, controlled by the periphery of the full wound bobbin, for actuating the locking device, head and tail stocks for engaging and rotating and releasing the bobbin, said engaging and rotating and releasing movements 100 being controlled by the carriage, a thread guide and means controlled by the carriage for removing the thread from the guide and carrying the same between the head piece and the end of the fresh bobbin.

9. In a bobbin winding machine, a reciprocating actuating member, a movable carriage, a device for locking the carriage with the actuating member, means, controlled by the periphery of the full wound 115 bobbin, for actuating the locking device, head and tail stocks for engaging and rotating and releasing the bobbin, said engaging and rotating and releasing movements being controlled by the carriage, a thread 120 guide, means controlled by the carriage for removing the thread from the guide and carrying the same between the head piece and the end of the fresh bobbin, and means for reengaging the thread with the thread 125 guide.

10. In a bobbin winding machine, a bobbin supporting, rotating and releasing device, a reciprocating and actuating member, a movable carriage, a device for locking the 130

- carriage with the actuating member, means, controlled by the periphery of the full wound bobbin, for actuating the locking device, a movable bobbin magazine and means controlled by the carriage for operating the magazine into and out of the delivery position.
11. In a bobbin winding machine, the combination of a bobbin driving head, and a tail stock, a pivotally supported bobbin magazine, means for swinging the same, means for releasing a bobbin from the magazine, and means for catching the released bobbin and delivering the same to the driving head and tail stock.
12. In a bobbin winding machine, a bobbin supporting, rotating and releasing device, a reciprocating actuating member, a movable carriage, means, controlled by the periphery of the full wound bobbin, for locking the carriage to the actuating member, a pivotally mounted bobbin magazine, means connected with the reciprocating carriage for swinging the magazine into and out of the delivery position and means for receiving the bobbin discharged from the magazine and delivering the same to the bobbin supporting, rotating and releasing device.
13. In a bobbin winding machine, a bobbin supporting, rotating and releasing device, a gravity feed bobbin magazine, means for normally supporting the lowermost bobbin in the magazine, adapted to be withdrawn from beneath said bobbin when the magazine is shifted, means for receiving the bobbin when released by the first supporting means and releasing the bobbin when the magazine is again shifted, and a cradle for receiving the released bobbin and for carrying the same to the bobbin rotating device.
14. The combination of an actuating member, a movable carriage, means for locking the carriage into operative relationship with the actuating member, means for engaging the periphery of the full wound bobbin for controlling the locking means, a head adapted to engage the bobbin, a driving shaft for the head and means controlled by the carriage for bringing the head into locking engagement with the driving shaft.
15. In a bobbin winding machine, a reciprocating actuating member, a movable carriage, means for locking the actuating member to the carriage in both directions of its movement, means actuated by the periphery of the wound bobbin for controlling the locking means, a bobbin engaging, rotating and releasing head and tail stock and means controlled by the reciprocated carriage for the control thereof.
16. In a bobbin winding machine, a reciprocating actuating member, a movable carriage, a device for locking the carriage with the actuating member, means, controlled by the periphery of the full wound bobbin, for actuating the locking device, and means for maintaining the locking device in locking position after a preliminary movement of the carriage and until a full forward and back reciprocation thereof.
17. In a bobbin winding machine, means for supporting, rotating and releasing the bobbin, a reciprocating actuating member, a movable carriage, a device for locking and unlocking the carriage with the reciprocating actuating member, means, controlled by the periphery of the full wound bobbin, for actuating the locking device, a thread guide and means controlled by the carriage for carrying the thread out of the guide and over the end of the bobbin.
18. In a bobbin winding machine, a reciprocating actuating member, a movable carriage, a device for locking the carriage with the actuating member, means, controlled by the periphery of the full wound bobbin, for actuating the locking device, a thread guide and means controlled by the carriage for carrying the thread between the head piece and the end of the bobbin.
19. In a bobbin winding machine, a reciprocating actuating member, a movable carriage, a device for locking the carriage with the actuating member, means, controlled by the periphery of the full wound bobbin, for actuating the locking device, a thread guide, means controlled by the carriage for carrying the thread from the thread guide to a position between the head piece and the end of the bobbin, and means controlled by the carriage for cutting the thread.
20. In a bobbin winding machine, means for supporting, rotating and releasing the bobbin, a reciprocating actuating member, a movable carriage, a device for locking the carriage with the actuating member, means, controlled by the periphery of the full wound bobbin, for actuating the locking device, a thread guide and means controlled by the carriage for carrying the thread out of the guide and over the end of the bobbin, and for reengaging the thread with the thread guide.
21. In a bobbin winding machine, a bobbin driving head and a coöperating tail stock, a reciprocating actuating member, a horizontally movable carriage, a device for locking the carriage with the actuating member in both directions of reciprocating movement, means, controlled by the periphery of the full wound bobbin, for actuating the locking device, and means controlled by the carriage for operating the tail stock to release a full bobbin and to engage an empty bobbin.

22. In a bobbin winding machine, a reciprocating actuating member, a movable carriage, a device for sometimes locking the carriage with the actuating member, means, controlled by the periphery of the full wound bobbin, for actuating the locking device, a head and tail stock for engaging, rotating and releasing the bobbins, a bobbin magazine and means controlled by the carriage for actuating the magazine to deliver bobbins to the head and tail stock. 25
23. In a bobbin winding machine, a reciprocating actuating member, a movable carriage, a device for locking the carriage with the actuating member, means, controlled by the periphery of the full wound bobbin, for actuating the locking device, a head and tail stock for engaging, rotating and releasing the bobbins, a bobbin magazine and means controlled by the carriage for actuating the magazine to deliver bobbins to the head and tail stock, and means controlled by the carriage for actuating the head and tail stock with respect to their en- 30
- gaging, disengaging and rotating movements. 35
24. In a bobbin winding machine, the combination of a head and tail stock adapted to engage, rotate and release the bobbin, the head provided with a pair of lugs and means for stopping the head with the lugs in position to support the thread when the same is brought between the head and a new bobbin. 40
25. In a bobbin winding machine, in combination with means for supporting, rotating and releasing the bobbin, a horizontally movable carriage, a reciprocating actuating member, a counter-balanced device for locking the carriage to the actuating member in both directions of its actuation and means controlled by the periphery of the wound bobbin for controlling the locking device. 45
